UNITED STATES PATENT OFFICE.

WILLIAM A. VALENTINE, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

DIE-FITTING APPARATUS.

Application filed March 13, 1920. Serial No. 365,383.

To all whom it may concern:

Be it known that I, WILLIAM A. VALENTINE, a citizen of the United States, residing at Philadelphia, county of Philadelphia,

5 State of Pennsylvania, have made a certain new and useful Invention in Die-Fitting Apparatus, of which the following is a specification.

This invention relates to die fitting apparatus, and particularly to apparatus to enable large heavy male and female steel or other metal dies to be accurately fitted together.

10 The object of the invention is to provide an apparatus in which heavy steel and other dies may be accurately fitted together before they are mounted in the die press, and which apparatus is simple in structure and efficient in operation.

20 Other objects of the invention will appear more fully hereinafter.

The invention consists substantially in the construction, combination, location and relative arrangement of parts, all as will 25 be more fully hereinafter set forth, and shown in the accompanying drawings and finally pointed out in the appended claims.

In the drawings:—

Fig. 1 is a view in front elevation of a 30 die fitting apparatus embodying the principles of my invention.

Fig. 2 is a broken detail view in section on the line 2, 2, Fig. 1, looking in the direction of the arrows, and showing the manner of connecting the die carrying block to one of its supporting and actuating screws.

Fig. 3 is a view in side elevation of the apparatus;

Fig. 4 is a view in vertical section through 40 the gearing for actuating the screws which support the die carrying block;

Fig. 5 is a view in perspective of a die carrying block detached from the apparatus;

45 Fig. 6 is a view in top plan of an auxiliary die supporting plate which, if desired, may be carried by the main die carrying block, a part being shown in section on the line 6, 6, Fig. 7;

50 Fig. 7 is a side view of the same, partly in section, on the line 7, 7, Fig. 6;

Fig. 8 is a perspective view of a base plate for supporting one of the dies to be fitted; The same part is designated by the same reference numeral wherever it occurs 55 throughout the several views.

In the manufacture of sheet steel stampings, and particularly stampings of large size, as well as of irregular shape, it is the practice to employ dies, the male and female members of which fit accurately together and when placed in a die press in proper relation to each other and brought together with a sheet steel plate between them, the sheet steel plate is drawn or 60 pressed into the shape determined by the contour of the die surfaces. Experience has shown that the best results are secured by employing solid instead of sectional dies as thereby the trouble is avoided of forming 65 creases or lines in the stamping or drawn product due to the pressure of seams and joints in the die surfaces. It has been attempted to employ sectional dies for such work and to fill up the joints or seams in 70 the die surfaces where the die sections come together, but this practice does not always remove the trouble and has been found in many cases to be unsatisfactory and to lead to additional expense in removing from the 75 stampings produced ridges or other markings produced therein by the joints or seams or the filling therefor in the die surfaces. For these and other reasons I have found it more economical and more satisfactory to make the dies in single pieces instead of in sections. This, however, necessitates the employment of large heavy die castings.

It is necessary to accurately fit together 90 the male and female members of the dies before they are employed for production, and this necessity applies not only to single piece die members but also to die members made in sections.

95 Heretofore it has been the custom and practice to mount the male and female members of the die in the die press and then to accurately fit the two together by cut and try, the two die faces being painted or coated over with a suitable material and then brought together and any inaccuracies in 100

their fitting together will be shown by the paint or coat material. Then by filing, cutting or otherwise, the die surfaces are brought more nearly into accurate fit with each other and the painting or coating impression and filing or cutting operations are repeated over and over again until finally the desired accurate register and fit of the two die faces is attained. This operation is necessarily slow and tedious, and, of course, while being carried on in the die press, the press itself is out of commission for production, sometimes for many hours, and even for days, while the die fitting operations are proceeding. This is a serious objection in a large establishment where rapid quantity production is important. Again, the die presses are large and expensive machines and while out of commission for production they represent loss in investment during the time they remain idle, and it is not economical nor efficient practice for a plant to carry spare die presses. Moreover, where large and heavy die members are employed, the work of fitting the dies together is rendered exceedingly difficult and the time required is materially increased, where the dies are fitted together while in the presses because of the lack of available space between the die surfaces for carrying on the fitting operations, even when the die members are separated to the utmost extent permitted by the press structure, for presses ordinarily are constructed to permit only a sufficient maximum separation of the die members to accommodate the insertion and removal of the work between and from the dies.

To overcome these practical objections, and they are, and I have found them to be, serious objections, I propose to provide an apparatus in which the die fitting operations may be carried on and accomplished before the dies are mounted in the die press. And, in accordance with my present invention, I employ a simple inexpensive structure for this purpose which permits sufficient separation of the die members to afford ample room and space between the die surfaces in which to effect the die fitting, filing and cutting operations. By employing such an apparatus, and effecting the die fitting operations therein before the dies are mounted in the presses, it is not necessary to interrupt the production operation of a press except merely to effect a removal of one set of dies therefrom and the substitution of a new set of dies which have already been accurately fitted together. In other words the die fitting operations have been accomplished outside of the press itself, and the useful production work of the press has not been interrupted or suspended to allow the die fittings to be effected in the press.

In the drawings I have shown a simple structure of die fitting apparatus which em-

bodies in one form the principles of my invention and wherein I employ a base 10, which, if necessary, may be suitably anchored, as, for example, by headed anchor bolts (not shown) received in the slots 11. Upon this base I erect the opposing vertical side standards 12, having guides 13 on their opposed vertical faces. A die supporting block 14 is mounted between the standards 12, and is formed with channel ways 15 in its ends which fit to and slide upon the guides 13 of the standards. The block 14 is carried by vertical screw rods 16, one at each end, by which it is raised and lowered as required. The block supporting screws 16 may be attached to the die carrying block in any suitable or convenient manner. A simple arrangement is shown, see Fig. 2, wherein the lower end of the screw projects into a chamber 17 of the block 14 and a collar or other abutment 18 is mounted on the end of the screw rod inside this chamber. This upper end wall of the chamber bears or seats upon this collar, thus forming a suspended support for the block while at the same time permitting relative movement of the screw rods and block. The screw rods are preferably held against rotation. This may be accomplished in any suitable or convenient manner, such, for example as by providing a rib or spline 19 on the screw rods which fit in grooves 20 in the holes in the ends of the block thorough which the screw rods project.

The die carrying block 14 may be raised and lowered, as may be required, by any suitable arrangement of raising and lowering mechanism. A simple arrangement is shown as a practical and operative embodiment of my invention wherein I mount a rotatable worm gear nut 21, see Fig. 4, upon each screw rod, the interior threads of the gear nut hub engaging the exterior threads of the screw rod. The worm gear nut 21 is mounted upon, and its hub is received in a seat formed in a frame member 22 which connects the upper ends of the vertical side standards 12. The worm gear nut 21 is rotated by means of a gear wheel 23, mounted upon a shaft 24 which is journaled in bearings carried by brackets 25, bolted to the frame member 22. It will be understood, of course, that a worm gear nut 21 and a drive gear 23 therefor is associated with each screw rod. Each gear nut 21 and its associated gear 23 is preferably enclosed within a casing 26 to protect them from dust and dirt. If desired, and in order to reduce friction, the thrust upon the rotatable worm gear nuts may be taken upon an anti-friction bearing such, for example, as the roller bearing indicated at 27, and the casing 26 may be utilized as a chamber to contain a lubricant for the various working parts of the gearing.

The operating shaft 24 may be driven in any suitable manner, and from any convenient source of power. I have shown a simple drive arrangement which I have found satisfactory wherein an electric motor 28 is mounted on a bracket 29, adjustably supported by a screw rod, (see Fig. 3) on one of the standards 12, and is geared by means of a belt 30, to a pulley 31, on the shaft 24. Since the motor 28 is adjustable with reference to the standard 12 it may be moved back and forth to vary the tension of the driving belt 30.

The die members to be fitted together are respectively mounted on the block 14 and base 10, and secured thereon in any suitable or convenient manner. I have shown the lower face of the die supporting block 14 provided with T-shaped grooves 32, adapted to receive headed bolts, not shown, for the purpose of attaching the die member to the block 14. In like manner I form the upper surface of the base 10 with similar T-grooves 33 for the purpose of securing the other die member in place thereon.

If desired, a separate and independent plate 34, see Figs. 6 and 7, may be applied to either the base 10, or the lower face of the block 14, for instance, by bolts passing through suitable bolt holes provided in the plate 34 and having their heads received either in slots 33 or 32 of base 10 or block 14 and the die member to be fitted secured to the auxiliary plate by means of bolts to be received in slots 35 in the face of the auxiliary plate. By this arrangement the auxiliary plate may be removed from the base 10 or block 14 without removal of the die member from the auxiliary plate, and said auxiliary plate and die member secured thereto removed together and transported to and mounted together in the die press. This affords a most convenient arrangement for removing the die members from the fitting apparatus after the fitting operations are completed and mounting them in the die presses.

Since the apparatus is not called upon to exert any pressing action the duty of the motor 28, acting through the screw rods 16, is merely that of raising and lowering the block 14, and, consequently, only a very small capacity motor may be used, and the screw connections 16 and the driving mechanism for the worm nuts acting thereon, may be made correspondingly light in weight and very much lighter than if a pressure function were to be accomplished. In operation, one member of the dies to be fitted together is fastened in the base plate 10 and the other member is mounted upon the block 14. The surface of one or the other or both the dies to be fitted together is then coated over with a suitable paint composition and the block 14 is then lowered until contact is made between the surfaces. The

danger of injuring the die surfaces by continued application of the power which controls the downward movement of the block 14, and after the die surfaces are brought into contact with each other, is obviated by reason of the loose connections between the screw rods 16 and the block 14.

While I have described my invention as applied to the fitting together of single piece die members, it will be understood, of course, that it is equally well adapted for use in fitting together separate cooperating pairs of members of sectional dies.

Having now set forth the objects and nature of my invention, and a construction embodying the principles thereof, what I claim as new and useful and of my own invention and desire to secure by Letters Patent is:—

1. In a die fitting apparatus, a base having means to secure thereto one member of the die to be fitted, a block having means to secure thereto the other die member to be fitted, screw rods having engaging connections with said block permitting relative movement of block and rods longitudinally of the rods, and gearing for moving said screw rods.

2. In a die fitting apparatus, a base having means to secure thereto one member of the die to be fitted, a block having means to secure thereto the other die member to be fitted, screw rods having engaging connections with said block permitting relative movement of block and rods longitudinally of the rods, worm gear nuts engaging said screw rods, and means to rotate said nuts.

3. In a die fitting apparatus, a base having means to secure thereto one member of the die to be fitted, a block having means to secure thereto the other die member to be fitted, screw rods having engaging connections with said block permitting relative movement of block and rods longitudinally of the rods, means to hold said screw rods against rotation relative to the block, a worm gear nut engaging each rod, and means to rotate said worm gear nuts.

4. In a die fitting apparatus, a base having means to secure thereto one member of the die to be fitted, a block having means to secure thereto the other die member to be fitted, screw rods having engaging connections with said block permitting relative movement of said block and rods longitudinally of the rod, worm gear nuts engaging said screw rods, a casing enclosing said nuts, and means to rotate said nuts.

5. In a die fitting apparatus, a base having means to secure thereto one member of the die to be fitted, a block having means to secure thereto the other member to be fitted, screw rods having engaging connections with said block permitting relative movement of said block and rods longitudi-

- nally of the rods, worm gear nuts engaging said screw rods, a drive gear for each nut, a casing enclosing each nut and its drive gear, and means for driving said drive gear.
- 5 6. In a die fitting apparatus, a base having means to secure thereto one of the die members to be fitted, a block having means to secure thereto the other die member to be fitted, screw rods engaging said block so as 10 to permit relative movement of block and rods longitudinally of the rods, worm gear nuts engaging said screw rods, means to rotate said nuts and an anti-friction thrust bearing for each nut.
- 15 7. In a die fitting apparatus, a base, vertical standards having guides, a traveling block having guideways at the ends thereof, and fitting between and engaging the guides on said standards, suspending screw rods 20 connected to the ends of said block so as to permit relative movement of rods and block longitudinally of the rods, said screw rods being held against rotation, a worm gear nut mounted upon each screw, a drive gear meshing with each nut, a shaft upon which said drive gears are mounted, and means to drive said shaft.
8. In a die fitting apparatus, a base, vertical standards having guides, a traveling block 30 having guideways at the ends thereof, and fitting between and engaging the guides on said standards, screw rods connected to the ends of said block and suspending the same, said rods being so connected to the block as 35 to permit relative movement longitudinally of the rods, said screw rods being held against rotation, a worm gear nut mounted upon each screw, a drive gear meshing with each worm gear nut, a shaft upon which said 40 drive gears are mounted, and means to drive said shaft, said base and block having grooves upon their opposed faces to afford means to secure thereto the die members to be fitted.
- 45 9. In a die fitting apparatus, a base, a die member supporting block, screw rods having loose connections with said block to move the same towards and from the base capable of independent longitudinal movement relatively thereto, an auxiliary plate for detachable attachment to either the base or the block, and having means to secure a die member thereto, and means to operate said screw rods.
- 55 10. In a die fitting apparatus, a base, and a supporting block, said parts having means to attach thereto the die members to be fitted together, screw rods having their ends extending into the ends of the block and 60 carrying collars to engage and support the block, and means to operate the screw rods to move the block towards and from the base.
11. In a die fitting apparatus, a base, and a supporting block, said parts having means to attach thereto the die members to be fitted together, screw rods having their ends extending into the ends of the block and carrying collars to engage and support the block, means engaging the screw rods to 65 retain the same against rotation, and gearing to move the screw rods to shift the block towards and from the base.
12. A die fitting apparatus comprising a base, a carrier vertically movable with respect to said base, a screw rod connected to said carrier to move the same towards and from the base, and an auxiliary plate for detachable attachment with either the base or the carrier said auxiliary plate having 70 means to secure a die member thereto, and means to operate said screw rod.
13. A die fitting apparatus comprising a base, means for securing one member of the dies to be fitted to said base, a vertically 75 movable carrier, means for securing the other member of the die to be fitted to said carrier, and means for raising and lowering said carrier, said means having a slip connection with said carrier.
14. A die fitting apparatus comprising a base, means for securing one of the dies to be fitted to said base, a pair of vertical standards, a movable carrier guided at its 80 ends on said standards, and means for raising and lowering said carrier, said means having a slip connection therewith, and means for securing the other of the dies to be fitted to said carrier.
15. A die fitting apparatus comprising a base having means for securing thereto one member of the dies to be fitted, vertically 85 disposed standards spaced widely apart from each other, a vertically movable carrier having means for securing thereto the other member of the dies to be fitted, and said carrier being guided at its ends by said standards, screw rods connected to said carrier to raise and lower the same, said rods arranged and operating to raise said carrier to a height above the base to accommodate workmen between the surfaces of the dies to be fitted when the carrier is raised, to accomplish the fitting operations on the opposed die surfaces, and means for actuating 90 said screw rods.
- In testimony whereof I have hereunto set my hand on this 9th day of March, A. D. 1920.
- 110 WILLIAM A. VALENTINE.
